[57] CLAIM

The ornamental design for an arm support with control panel, as shown and described.

DESCRIPTION

FIG. 1 is a perspective view of an arm support with control panel showing my new design;

FIG. 2 is a top plan view thereof;

FIG. 3 is a bottom view thereof;

FIG. 4 is a rear view thereof;

FIG. 5 is a front view thereof;

FIG. 6 is a side elevational view thereof;

FIG. 7 is a side elevational view of the other side thereof;

FIG. 8 is an enlarged perspective view of the control panel shown in FIG. 1 when disconnected from the arm support;

FIG. 9 is a top view thereof;

FIG. 10 is a bottom view thereof;

FIG. 11 is a front view thereof;

FIG. 12 is a rear view thereof;

FIG. 13 is a side elevational view thereof;

FIG. 14 is a side elevational view of the other side thereof;

FIG. 15 is a perspective view of a further embodiment of the arm support with control panel shown in FIG. 1;

FIG. 16 is a top plan view thereof;

FIG. 17 is a bottom view thereof;

FIG. 18 is a rear view thereof;

FIG. 19 is a front view thereof;

FIG. 20 is a side elevational view thereof;

FIG. 21 is a side elevational view of the other side thereof;

FIG. 22 is an enlarged perspective view of the control panel shown in FIG. 15 when disconnected from the arm support;

FIG. 23 is a top view thereof;

FIG. 24 is a bottom view thereof;

FIG. 25 is a front view thereof;

FIG. 26 is a rear view thereof;

FIG. 27 is a side elevational view thereof; and,

FIG. 28 is a side elevational view of the other side thereof.
